UNITED STATES PATENT OFFICE.

HENRY POCOCK, OF LONDON, ONTARIO, CANADA.

BUILDING-BLOCK MACHINE.

971,213.

Specification of Letters Patent. Patented Sept. 27, 1910.

Application filed October 2, 1908. Serial No. 455,928.

To all whom it may concern:

Be it known that I, HENRY POCOCK, a subject of the King of Great Britain, and a resident of the city of London, in the 5 county of Middlesex, in the Province of Ontario, Canada, have invented a new and useful Building-Block Machine, of which the following is a specification.

This invention relates to a machine for 10 making blocks of cement or concrete.

The object of the invention is to provide mechanism for rolling the cement or concrete block from its molded to its discharging position in such a manner that the 15 freshly molded cement block is carried by the machine instead of by the arms of the operator, which makes this part of the operation connected with the manufacture of building blocks in this machine light and 20 easy for the operator, and the operation of rolling being the application of all parts of a curved surface to a plane, the block is smoothly, easily, quickly and gradually delivered to its discharging position, and being 25 thus delivered there is no likelihood of the freshly molded block being jarred to cause it to break or collapse, practically therefore, every block made on this machine is perfect.

30 A further object of the invention is to so construct and arrange this machine that the face of the block will be in the bottom of the mold, and thus make it a "face down" machine or one in which the blocks 35 may be faced in the most efficient and rapid manner with a richer material than the body of the block, if required.

A further object of the invention is to adapt the core to be placed at any position 40 in the block, and in such a manner that any size of core can be used in any size of block, and thus meet every architectural requirement such as a small core opening where great crushing strength is required.

45 A further object is to adapt a core to be withdrawn vertically thus permitting the use of wetter material, if required, in manufacturing building blocks, and the removal of the core vertically from the freshly 50 molded block, after the block is rolled from its molded to its discharging position, avoids and completely prevents any possibility of said freshly molded block from collapsing, which it would be very likely to do if the 55 core was withdrawn horizontally from a freshly molded block before the latter was

moved from its molded to its discharging position.

A further object of the invention is to make blocks for all widths of walls with the 60 one mold by adjusting the same according to the width of wall required.

A further object is to make blocks for all widths of walls on the one width of pallet, one set of pallets therefore 65 only being required to make all widths of blocks with this machine, instead of a set of pallets for each width of block.

A further object is to adapt the mold to make blocks of any length, form or design 70 and at the same time provide a machine that will be simple, strong and durable in construction, inexpensive to manufacture, and efficient in practical use. And this invention consists of the improved construction and 75 novel combination of parts of the same as will be hereinafter first fully set forth and described and then pointed out in the claims.

Reference is had to the accompanying drawings forming part of this specification 80 wherein:

Figure 1 is a side view of a machine embodying my invention. In this view the block is shown in its discharging position. Fig. 2 is another view of same showing the 85 block in its molded position. In this view the hinged side or door is shown open. Fig. 3 is a plan view of the machine adjusted as shown in Fig. 1. In this view the block shown in Fig. 1 is removed. Fig. 4 is a 90 plan view of the machine adjusted as shown in Fig. 2. In this view the block is not shown, and the handles which are used to steady the rolling frame are cut away. Fig. 5 is a detail vertical sectional view of the 95 machine on the line x, x , of Fig. 1. Fig. 6 is a detail side view of the rolling frame and attachments. Fig. 7 is a detail side view of the rolling frame and track illustrating the operation of the rolling frame on 100 said track. Fig. 8 is a detail perspective view of the track frame. Fig. 9 is a detail perspective view of the rolling frame. Fig. 10 is a detail plan view of the back plate 105 of the mold, illustrating the extensions at each end by which the back plate of the mold is lengthened to make blocks of greater length, Fig. 11 is a detail plan view of the front plate of the mold, illustrating the extensions at each end of said front plate, by 110 means of which the front side of the mold is lengthened to make blocks of greater

- length. Fig. 12 is a detail plan view of a frame which is secured in place between the bracket on the rolling frame and the face plate when making thin veneer blocks. Fig. 5 13 is a detail view of the bracket, the face plate, and the veneer block frame shown in Fig. 12, illustrating the position of said frame between said bracket and said face plate.
- 10 In the accompanying drawings: The numeral 1 indicates the main frame of the machine to the upper side of which the track frame 2 is secured, and, *a*, are the longitudinal sides of 2.
- 15 3, 3 indicate spaced apart tracks with which the track frame 2 is provided. 4 a socket at one end and 5 a shoulder at the other end of each of said tracks 3.
- 6 indicates a rolling frame provided with 20 the spaced apart curved segments 7, which segments 7 are so arranged on said rolling frame 6 that their curved faces, *b*, will rest on the tracks 3.
- 25 *c*, designates a raised or projecting flange or rib with which the inner edge of the curved face of each of the segments 7 is provided, and said flanges or ribs, *c*, are fitted to and adapted to rest against the inner adjacent sides of the tracks 3, to guide 30 and hold the curved faces, *b*, of said segments 7 in place and to prevent them from slipping or running off the tracks 3, as they roll backward and forward on said tracks.
- 35 8 indicates a tongue with which one end of each of said segments 7 is provided, and said tongues are fitted to and adapted to engage with the socket 4 in the tracks 3.
- 9 indicates spaced apart hooked or shou- 40 dered hangers with which the rolling frame 6 is provided, the shoulders, *d*, of which hangers are adapted to engage with the underside of the sides, *a*, of the track frame 2, to prevent excessive movement of said rolling frame 6; and a spring *d'*, shown in 45 Fig. 9, held in place on said shoulder *d*, of said hanger 9, and adapted to engage with the under side of frame 2 may be used to ease the jar of the rolling frame 6 at the end of the operation of discharging the 50 mold; and 10 are handles which are grasped by the operator to operate and control the speed at which the rolling frame 6 moves.
- 11 indicates a shoulder, 12 a series of screw threaded bolt holes, and, *t*, a series of 55 pin holes with which each of the opposite longitudinal sides, *e*, of the rolling frame 6 are provided.
- 13 indicates a bottom or face plate sup- 60 porting bracket, which bracket is bolted to the rolling frame 6 by the screw threaded bolts, *i*, extending through bolt holes in said bracket 13 and into one of each of the series of opposite screw threaded bolt holes 12 in the opposite longitudinal sides, *e*, of said 65 rolling frame 6, and *m*, indicates pins se- cured to said bracket 13 which pins are fitted to and inserted in the pin holes, *t*, in the rolling frame 6, to assist in firmly holding and securing said bracket in place.
- 14 indicates a face plate removably se- 70 cured to the upper side of said bracket 13 by the screw bolts 15 extending through bolt holes in the plates 16, which rest against the lower side of said bracket 13, and into screw threaded sockets, *j*, in the back of said face plate 14.
- 17 indicates a pallet formed of wood or other suitable material and provided with the battens or strips, *f*, thereon, which pallet is supported on the frame 6 and rests against 80 the shoulders 11 of the rolling frame 6 when the latter is in the position shown in Fig. 1, but which pallet 17 is supported on the shoulders 11 of and rests against the inner side of the rolling frame 6 when the latter 85 is in the position shown in Fig. 2; and this pallet 17 is securely held in this upright position from accidentally falling from a vertical to a horizontal position when the rolling frame 6 is being adjusted to the position shown in Fig. 2, by being inserted between said rolling frame 6 and a portion of the adjacent face of the bracket 13.
- 18 indicates the back plate of the mold which is bolted or otherwise rigidly and 90 permanently secured to the track frame 2, and on the inner face of said back plate 18 narrow beads, *g*, are formed if desired to form shallow cement receiving and holding 95 grooves, *h*, in building blocks 34 formed in 100 this machine.
- 19 indicate perforated lugs secured to the outer side of the back plate 18 of the mold, and 20 perforated lugs secured to the swinging doors 21, through which perforated lugs 105 19 and 20 a rod 22 extends to pivotally secure said swinging doors 21 of the mold to said back plate 18.
- 23 indicate removable end plates, which are rigidly secured to the inside of the 110 swinging doors 21 by screw bolts 24 extending through plates 25 resting against the outside of said doors 21 and into screw threaded sockets in said end plates.
- 26 indicate locking levers one of which is 115 pivotally mounted on a pivot bolt 27 secured to each of the swinging doors 21, and, *n*, indicates an inclined rib and, *o*, a cam face formed on each of said locking levers 26. 28 indicate locking flanges one of which 120 is formed on the outer side of and near each end of said rolling frame 6 and in line with the locking levers 26 pivotally mounted on the swinging doors 21, so that when said swinging doors 21 are closed, by pressing 125 down the outer ends of said levers 26 the ribs, *n*, will abut against the inner adjacent sides of and the cam faces, *o*, engage with and bind on the front sides of said locking flanges 28 and lock the front, back and end 130

plates of the mold rigidly together, the ribs, *n*, preventing any possibility of the doors 21 accidentally swinging outward from any cause when so secured together.

5 29 indicate extension plates, one of which is rigidly secured to each end of the back plate 18 by the bolts 30 for the purpose of lengthening said back plate 18 and consequently the length of the mold at the back, 10 and said extension plates 29 are each provided with perforated lugs, *r*, similar to and for a similar purpose as the perforated lugs 19 secured to said back plate 18.

31 indicate extension plates which are secured to the outer face of, and near each of the side edges, of the rolling frame 6 by the bolts 32, for the purpose of increasing the width of the rolling frame at a point opposite the back plate 18, and the rolling frame 20 6 serving as the front plate of the mold, the width of the front plate of the mold is consequently increased. And said extension plates 31 are each provided with a locking flange, *s*, in a similar position and for a similar purpose as the locking flange 28 on the rolling frame 6, and, *v*, a recess formed in each of said extension plates 31 to receive the locking flange 28 over which they are placed.

30 33 indicates the vertically removable core, and 34 the cement or concrete block formed by this machine.

35 35 indicates a supplemental frame which is interposed between the plates 16 and the face plate 14, to raise said face plate 14 in the mold for the purpose of making a thin or veneer block on this machine.

In a machine constructed as described, the blocks are rolled from their molded to their 40 discharging position, the advantages of which are hereinbefore set forth, and the curved segments 7 being provided with the flanges, *c*, are retained on the tracks 3 without any effort on the part of the operator.

45 And in this machine the bottom plate 14 of the mold forms the face of the block, and said bottom or face plate 14 is secured to and supported by the bracket 13, and said bracket 13 is secured to the rolling frame 6, 50 by the bolts, *i*, engaging with one of the series of bolt holes 12 formed in opposite sides of said rolling frame 6, so that by removing the bolts, *i*, the bracket 13 as well as the face plate 14 secured thereto, may be

55 adjusted upward or downward on said rolling frame 6, and held at the position to which it is adjusted by engaging the bolts, *i*, with one of the series of screw threaded bolt holes 12 in the opposite sides of said rolling frame 6. And this being a "face down" machine, or one in which the bottom plate of the mold forms the face of the block, the width of said block will be the distance from said face plate 14 to the top of the back 60 plate 18, so that by adjusting the bracket 13,

on which said face plate 14 is mounted, upward or downward, cement or concrete blocks of varying width may be formed in the one mold, and a further variation in the width of the cement or concrete blocks may 70 be formed by inserting the supplemental frame 35 between the bracket 13 and the face plate 14, when so arranged the distance from the face plate 14 to the top of the back plate 18 will be considerably reduced, after 75 which by adjusting said bracket 13 on said rolling frame 6 thin veneer blocks of varying thickness may be formed, thus adapting the one mold to make blocks for all widths of walls by adjusting the same according to the 80 width of wall required. Again by securing extension plates 29 and 31 to the back plate 18 and rolling frame 6, respectively, blocks of varying lengths as well as blocks of varying widths may be formed on the one mold. 85 And the face plate 14 being removably secured to the bracket 13 by the bolts 15 and plates 16, one face or bottom plate 14 may be readily and easily removed, and another face plate with any pattern or design formed 90 thereon may be secured to said bracket 13, thus readily and easily adapting this mold to make blocks with any required design or pattern on their face. And further, in a machine constructed as described, the pallet 17 95 is held between the rolling frame 6 and a portion of the bracket 13, and its lower edge is supported on the shoulder 11, consequently this pallet 17 extends from the top of the rolling frame 6 to a point below the face plate 14, as shown in Fig. 2, one set of pallets therefore will only be required to make all widths of blocks with this machine, a great saving is thus effected over machines in which a set of pallets is required for each 100 width of block.

In operating this machine the rolling frame 6 is adjusted to the position shown in Fig. 2 the swinging end doors 21 to the position shown in Fig. 4, and the whole are rigidly 110 and firmly held together by engaging the locking levers 26 with the locking flanges 28. The mold thus formed is partly filled with cement composition and tamped down, and the core 33 inserted or lowered vertically and 115 placed horizontally therein to the position shown in Fig. 2, this insures the perfect tamping of the portion of the cement block below the core, the mold is then filled with cement composition tamped down, struck off, 120 the locking levers 26 are disengaged from the locking flanges 28, and the rolling frame carrying the block is rolled from the position shown in Fig. 2 to the position shown in Fig. 1, the core 33 is then removed vertically 125 from the block and the pallet and block placed to one side out of the way to dry.

When operated as described the core 33 is inserted vertically and placed horizontally in the mold and raised vertically out of the 130

block after the freshly molded cement block 34 has been rolled from its molded to its discharging position, and this removal of the core 33 vertically after said freshly molded 5 cement block 34 has been rolled from its molded to its discharging position, permits the use of wetter material, if required, in manufacturing building blocks, and also completely prevents any possibility of said 10 freshly molded block from collapsing which as before stated it would be very likely to do if the core was withdrawn horizontally from a freshly molded cement block before the latter was removed from its molded to its dis- 15 charging position. And as herein set forth, the core 33 is inserted vertically and placed horizontally in the mold, and being so placed in position, any size of core may be used in any size of block, and thus readily and easily 20 meet every architectural requirement such as a small core opening where great crushing strength is required, as well as other practical advantages which are hereinbefore set forth, and at the same time provided a "face 25 down" block machine that will be simple, strong and durable in construction, inexpensive to manufacture and efficient in practical use for simplicity in adjustability, wide range of blocks, ease of operation and large 30 capacity per day.

Having thus described my invention, I claim:

1. A machine for molding blocks embodying a support, a frame mounted upon said 35 support and having the forward portion thereof provided with means to constitute a pair of tracks, each of said stationary tracks having a socket at one end and a shoulder at the other end, a vertically disposed plate 40 fixedly secured to said frame, and constituting the back wall of a mold, a plate hinged to each end of said back plate and constituting the ends of a mold, a rolling frame

provided with a pair of segments traveling upon said tracks said segments provided 45 with tongues adapted to engage in said sockets when the rolling frame is in one position and said segments adapted to abut against said shoulders when the rolling frame is in the other position, a bracket fixedly secured to said rolling frame and forming in connection with said frame a pocket, a plate connected to said bracket and constituting the bottom of the mold, a removable pallet mounted in said pocket and constituting the 50 front of the mold, and means carried by the hinged plates and engaging the pallet coupling the front and ends of the mold together.

2. A machine for molding blocks embodying a support, a frame mounted thereon and provided with means to constitute a pair of tracks, a vertically-disposed plate secured to said frame and constituting the back wall of a mold, a pair of plates connected to said 60 back plate and constituting the ends of a mold, a rolling frame provided with a pair of segments traveling upon said track, said segments and said tracks provided with means associating with each other for limiting the movement in either direction of said frame, a member connected to said rolling frame and in connection therewith forming a pocket, a plate connected to said member and constituting the bottom of the mold, a 65 removable pallet mounted in said pocket and constituting the front of the mold, and means for coupling the front and ends of the mold together.

In testimony whereof, I have signed in the 70 presence of the two undersigned witnesses.

HENRY POCOCK.
